UNITED STATES PATENT OFFICE.

ELLIOTT L. JAMES, OF LOWNDESBORO, ALABAMA.

STREET-CAR-DOOR-LOCKING DEVICE.

1,264,187.

Specification of Letters Patent. Patented Apr. 30, 1918.

Application filed August 8, 1917. Serial No. 125,091.

To all whom it may concern:

Be it known that I, ELLIOTT L. JAMES, a citizen of the United States, residing at Lowndesboro, in the county of Lowndes and 5 State of Alabama, have invented certain new and useful Improvements in Street-Car-Door-Locking Devices; and I do hereby declare the following to be a full, clear, and exact description of the invention, such as 10 will enable others skilled in the art to which it appertains to make and use the same.

This invention relates to improvements in a street car door locking device and has for one of its objects the provision of a device 15 of this character, whereby the door will be held from being opened while the car is in motion or traveling and which will automatically release the door when the car comes to a stop, thus obviating the danger 20 of the door being opened while the car is in motion or traveling.

Another object of this invention is the provision of a catch located adjacent the door and adapted to be moved into engagement 25 with the door while the car is in motion and to be automatically moved from engagement with the door when the car stops.

A further object of this invention is the 30 provision of means for moving the catch into engagement with the door and hold the same in this position while the car is in motion, and which will automatically move the catch from engagement with the door when 35 the car comes to a stop.

A still further object of this invention is the provision of a street car door operating device of the above stated character, which shall be simple, durable and efficient, and 40 which may be manufactured and sold at a comparatively low cost.

With these and other objects in view as will become more apparent as the description proceeds, the invention consists in certain 45 novel features of construction, combination and arrangement of parts as will be hereinafter more fully described and claimed.

For a complete understanding of my invention, reference is to be had to the following 50 description and accompanying drawings, in which:

Figure 1 is a longitudinal sectional view of a street car door locking device constructed 55 in accordance with my invention,

Fig. 2 is a transverse sectional view of the same.

Referring in detail to the drawings, the numeral 1 indicates a flooring of a street car or the like and 2 represents the door to 60 the car, which is of the swinging type.

The flooring 1 of the car adjacent its forward end is provided with a slot 3 for the purpose of receiving a lever 4, which is pivoted to the flooring 1 of the car as at 5. The 65 lever 4 has pivoted to its upper end, an arm 6, which is normally supported in a substantially horizontal position by its pivot and is adapted to be moved into and out of engagement with the door 2 as illustrated 70 in full and dotted lines in Fig. 1. A suitable guide 7 is secured to the free end of the arm 6 and is adapted to engage the flooring 1 for the purpose of aiding in supporting the arm in a substantially horizontal 75 position so that the same will efficiently hold the door in closed position.

Hangers 8 are secured to the floor 1 of the car and have slidably mounted therein, an operating rod 9, which is pivoted to the 80 lower end of the lever 4 as at 10. A cylinder 11 is supported to the flooring 1 of the car by hangers 12 and is provided with an elongated slot 13 for receiving a bar 14, which is pivoted to the free end of the operating rod 9. The cylinder 11 has one end 85 thereof closed by a head 15 and also has slidably mounted therein, a piston 16. The piston 16 is provided with the usual piston rod 17, which is secured to the bar 14. Supporting brackets 18 are secured within the cylinder 11 and slidably support a cylindrical member 19. The cylindrical member 19 has formed thereon, a rib 20, which slides in the grooves in the brackets 18 for preventing the cylindrical member 19 from rotating in said brackets. The cylindrical member 19 has one end closed by a wall 21, which is provided with an indentation 21' for the purpose of receiving the free end of 100 the piston rod 17. The inner wall of the cylindrical member 19 for a short distance is provided with screwthreads 22, which mesh with screwthreads 23 upon a shaft 24.

The shaft 24 constitutes the armature shaft 105 of a motor 25, which is supported to the flooring 1 of the car by hangers 26. The motor 25 is adapted to be electrically connected with the controlling mechanism of the driving motor of the car (not shown) 110

so that when the driving motor of the car is started in operation, the motor 25 will be also started, causing the screwthreads 23 to move the cylindrical member 19 forwardly to occupy a position as shown in dotted lines in Fig. 1. As the cylindrical member 19 moves forwardly, the piston 16 is moved forwardly into a dotted line position compressing air within the cylinder 11. 5 As the piston 16 moves forwardly, the arm 4 is rocked upon its pivot to cause the arm 6 to engage the door 2 and hold the same in a closed position. As the cylindrical member 19 moves into a position as shown in 10 dotted lines, the screwthreads 22 disengage from the screwthreads 23 preventing further movement of the cylindrical member and piston 16. When the driving motor (not shown) of the car is stopped by the 15 usual controlling means, the motor 25 is stopped and the compressed air within the cylinder 11 forces the piston 16 rearwardly, moving the cylindrical member 19 rearwardly, which rotates the shaft 24 in a reverse direction from the direction heretofore described, positioning the device ready to again be moved forwardly. As the cylindrical member 19 moves rearwardly under the influence of the piston 16, the 20 arm 4 is rocked upon its pivot, causing the arm 6 to move from engagement with the door 2 so that the door may be readily 25 opened.

From the foregoing description taken in 30 connection with the accompanying drawings, it will be noted that a means has been provided whereby the door 2 will be held in a closed position as long as the car is in motion and which will be automatically 35 released when the car stops.

While I have shown and described the preferred embodiment of my invention, it will be understood that minor changes in construction, combination and arrangement 40 of parts may be made without departing from the spirit and scope of the invention as claimed.

Having thus described my invention, what I claim is:

50 1. The combination with a car including a floor and a swinging door, of a catch pivoted to the flooring, a cylinder carried by the flooring, a piston in said cylinder, means for connecting the piston to the catch, and means for moving said piston forwardly to compress the air within said cylinder and simultaneously moving the catch into engagement with the door, and means for permitting the piston to move rearwardly under

the influence of the compressed air within 60 the cylinder to disengage the catch from the door of the car when the same has stopped.

2. The combination with a car including a flooring and a swinging door, of a catch 65 pivoted to the flooring, a cylinder carried by said flooring, a piston slidable in said cylinder, a cylindrical member slidably mounted within the cylinder, means connecting the piston with the catch, and means 70 for moving the cylindrical member forwardly to cause the piston to compress air within the cylinder and simultaneously move the catch into engagement with the door, and means for permitting the cylindrical 75 member to move rearwardly under the influence of the compressed air within the cylinder and simultaneously disengage the catch from the door when the car is stopped.

3. The combination with a car including 80 a flooring and a swinging door, of a catch pivoted to the flooring, a cylinder carried by said flooring, a piston in said cylinder, means connecting the piston with the catch, a cylindrical member slidably mounted 85 within the cylinder, screwthreads formed within the cylindrical member, a motor secured to the flooring, an armature shaft for said motor and disposed within the cylindrical member, screwthreads upon said shaft 90 and adapted to mesh with the screwthreads of the cylindrical member for forcing said cylindrical member forwardly, causing the piston to compress air within the cylinder and simultaneously move the catch into engagement with the door, and said screwthreads adapted to disengage each other upon the cylindrical member reaching its forward position to hold the catch in engagement with the door as long as the motor 95 is rotating, and said piston is adapted to move rearwardly under the influence of the compressed air when the motor has stopped to disengage the catch from the door.

4. A car door locking device comprising 105 a catch associated with a door, a cylinder, a piston in said cylinder and connected to the catch, a slidable means in said cylinder adapted to actuate the piston to move the catch in one direction to lock the door and 110 compress air within the cylinder, and means actuating said sliding member.

In testimony whereof I affix my signature in presence of two witnesses.

ELLIOTT L. JAMES.
